UNITED STATES PATENT OFFICE.

WALTHER MALZACHER, OF TRAISEN, AUSTRIA.

RUNNER BRICK AND PROCESS OF MANUFACTURING THE SAME.

Application filed January 12, 1923. Serial No. 612,362.

To all whom it may concern:

Be it known that I, WALTHER MALZACHER, a citizen of the Republic of Switzerland, and resident of Traisen, Lower Austria, Republic of Austria, have invented certain Improvements in Runner Bricks and Processes of Manufacturing the Same, of which the following is a specification.

In casting iron and more particularly 10 steel, a permanent base plate is used on which the mould and stand pipe are mounted; the stand pipe reaches to a level above that of the mounted tops, communication is established between the stand pipe and the 15 moulds by runner bricks provided with suitable passages namely main passages and branch passages, the main passages of each of the runner bricks communicating with the main passages of one or more adjacent 20 runner bricks and the branch passages communicating with the main passages of the bricks and with the moulds tightly fitted onto the same. The runner bricks are located in suitable grooves provided for this 25 purpose in the permanent base plate tightly fitting each other and the grooves.

In casting molten metal is poured into the stand pipe and flows through the main and branch passages of the runner bricks to 30 the several moulds mounted on the base plate. After the metal has set in the moulds and in the passages of the runner bricks, the latter and the moulds have to be removed, and fresh runner bricks have to be 35 brought into position in the base plate preparatory to a fresh casting, while the runner bricks once used must be broken to recover the metal set in their passages.

The runner bricks heretofore used were 40 made of fire brick or chamotte and thus were expensive and moreover they could not be made at the foundry whenever required but had to be ordered from special fire brick works.

In order to dispense with the runner 45 bricks, base plates were proposed in which either the entire base plate or part thereof were so constructed that the walls of the channels therein can be formed of refractory material which is heated in the requisite parts of the base plate, the requisite passages being produced therein. This, however, involves great expense as new base plates have to be substituted for those here- 50 tofore used.

The object of my invention is, while retaining the usual or existing base plates, to substitute for the expensive runner bricks, made of fire brick or chamotte, runner bricks which may be easily made in the 60 foundry from materials there ready at hand, so that any foundry may at once use my improved runner bricks with the existing base plates.

With this object in view my improved 65 runner brick consists of a rigid frame preferably of cast steel or steel sheet of the shape of the usual runner bricks made of fire bricks or chamotte, and filled with some suitable refractory moulding material such as 70 sand, loam or the like in which the required main and branch passages are formed in the usual way by cores.

Preferably sand moistened with sulfite lye 75 in the usual way is used as moulding material, and is pressed into the frames. The end faces and the top face of the frame are open and its bottom may be provided with an opening.

In the annexed drawings Fig. 1 is a perspective view of a constructional form of the rigid frame of my improved runner brick, Fig. 2 is a transverse section of the latter and Fig. 3 is a plan view of the base plate provided with my improved runner 80 bricks and mould mounted thereon. Fig. 4 is a perspective view of a modification of the rigid frame of my improved runner block, Fig. 5 is a transverse section thereof and Fig. 6 is a plan view of a runner brick. 90

Referring more particularly to Figs. 1 and 2 my improved runner brick consists of a rigid frame of an external configuration and dimensions the same as those of the fire brick or chamotte runner bricks heretofore 95 used with any given base plate. The frame shown in Fig. 1 is parallelopipedal in shape and has full side walls 1, 2 and a bottom wall 3 which may be provided with an opening 4; it is open at the top and end 100 faces and the side walls may be provided on top with inwardly projecting flanges 12, 13. This frame is filled with some suitable refractory moulding material 5 such as sand preferably moistened with sulfite lye or with 105 loam or the like, the usual main passages 6 and branch passages 7 by means of cores inserted before filling and pressing in the moulding material and then removed as is well known in making moulds. The open- 110

ing 4 in the bottom face 3 serves for compressing the moulding material within the frame but in many cases such compression is not necessary and then the opening 4 may be dispensed with.

The frame filled with moulding material with the main passages and branch passages provided therein is then preferably slightly heated if desired and is then brought into 10 the base plate 8 the same as the fire brick or chamotte runner bricks heretofore in use as is indicated in Fig. 3, where E indicates the stand pipe and K the casting moulds.

Instead of providing inwardly projecting 15 flanges 12, 13 at the top sides of the side walls 1 and 2, I may also make the side walls wedge shaped in transverse section tapering at the inside from top to the bottom or from top and bottom towards a line 20 at about the middle of the height of the mould as shown in Fig. 4. By this modified construction of the frame the same is strengthened and a more uniform compression of the moulding material is secured.

25 In some cases the runner bricks, more particularly those immediately below the stand pipe which are subject to the molten metal rushing downward through the stand pipe, it is advisable to provide below the branch passage 7, leading from the stand pipe to the main passage, a fire brick block 9 so as to form the bottom of the main passage 6 as shown in Fig. 5. In this case the bottom wall 3 is preferably provided 30 with inwardly projecting ribs 10 for preventing lateral displacement of the fire brick block 9.

In order to dispense with the application of loam or other plastic tightening material to the joints of the runner bricks the same may be provided at one end face of the filling material with a projection 11 and at the opposite end face with a corresponding recess 14, but as a rule this is not required with my runner bricks as sufficiently tight joints are obtained with plane end faces by applying some plastic loam to the end faces as usual.

The improved runner bricks above described are placed into the base plate and after casting they are removed therefrom in the same way as the chamotte runner bricks heretofore used. After removal the moulding material and the metal set in the 50 passages in the same are removed from the frames and the latter as well as the moulding material may be used over and over again.

60 Thus all the foundry requires is a comparatively very small stock of the rigid frames made of cast steel or sheet steel, the moulding material preferably sand being ready at hand in the foundry and all the runner bricks required may be readily made 65 from these materials at the foundry itself in

the simplest and cheapest manner, whereby a large saving is secured, and the foundry becomes independent of fire brick works furnishing the chamotte runner bricks heretofore used. Moreover if any change of the dimension and shape of the runner bricks is 70 desirable for any reasons all that is required is to cast a small number of fresh frames, which may be done without any difficulty in the foundry itself. This also permits the 75 making and using of frames representing a combination of a plurality of chamotte runner bricks whereby the number of joints may be reduced when the runner bricks are placed in the base plates.

80 Any suitable moulding material may be used, such as sand, loam or the like according to existing conditions. Normally the improved runner bricks are placed in the base plate with their open top face and the branch passages upwards, but whereas moulds are to be mounted on the runner bricks the latter are not provided with branch passages and may also be placed in the base plate with the bottom wall upwards.

85 What I claim is:

1. A runner brick consisting of a rigid metal frame filled with moulding material such frame being of a shape and the moulding material therein being provided with passages the same as chamotte runner bricks, the frame being open at the faces where the said passages lead to the outside.

2. A runner brick consisting of a rigid metal frame filled with moulding material, such frame being of a shape and the moulding material being provided with passages the same as chamotte runner bricks, the said frame being open at least two faces 105 where the said passages lead to the outside.

3. A runner brick consisting of a rigid metal frame filled with moulding material such frame being of a shape and the moulding material being provided with main and branch passages the same as chamotte runner bricks, the said frame being open at least two faces where the said passages lead to the outside, a refractory block being embedded in the filling material opposite the inner end of the branch passage, such refractory block forming the bottom of the main passage and resting upon the bottom of the frame.

4. A runner brick consisting of a rigid metal frame filled with moulding material, such frame being of a shape and the moulding material being provided with main and branch passages, the same as chamotte runner bricks, the said frame being open at 125 least two faces where the said passages lead to the outside, a refractory block being embedded in the filling material opposite the inner end of the branch passages, such refractory block forming the bottom of the 130

main passage and resting upon the bottom of the frame, between inwardly projecting ribs on the bottom wall of the said frame.

5. A runner brick consisting of a rigid metal frame filled with moulding material, such frame being of a shape and the filling material being provided with passages, the same as chamotte runner bricks, the said frame being open on top and at least one of

its sides and being provided with an open-¹⁰ ing in its bottom.

In testimony whereof I have signed my name to this specification, in the presence of two subscribing witnesses.

WALTHER MALZACHER.
